UNITED STATES PATENT OFFICE.

ALEXANDER S. LOCKE, OF NEW YORK, N. Y., ASSIGNOR TO THE NEW HAVEN
CLOCK COMPANY, OF NEW HAVEN, CONNECTICUT.

DESIGN FOR A CLOCK-CASE.

SPECIFICATION forming part of Design No. 15,976, dated March 17, 1885.

Application filed February 16, 1885. Term of patent 7 years.

To all whom it may concern:

Be it known that I, ALEXANDER S. LOCKE, of New York, in the county of New York and State of New York, have invented a new Design for Clock-Cases; and I do hereby declare the following, when taken in connection with the accompanying drawing and the letters of reference marked thereon, to be a full, clear, and exact description of the same, and which 5 said drawing constitutes part of this specification, and represents a front perspective view.

This invention relates to a design for a clock-case; and it consists in the configuration of the clock and the ornament thereon, as shown 10 in the accompanying illustration and herein-after described.

Upon a suitable base, A, the body B of the clock rests. The body is in the shape of a sphere, showing the dial upon its surface. 15 Upon the top of the sphere stands a figure in

the attitude of balancing, as if it retained the sphere in a stationary position upon its base. To make the apparent efforts of the figure more clear, the upper surface of the base is inclined, so that if the sphere were free it would naturally roll from the base; but I do not wish to limit the design to such an inclined surface of the base. 25

What I do claim is—

The herein-described design for clock-cases, 30 consisting of the body of the clock, of spherical shape, resting upon a base, with a figure in the attitude of balancing upon the top of the sphere, as shown in the accompanying illustration.

ALEX. S. LOCKE.
